MULTIPLE HEAT EXCHANGE UNIT

Ferdinand B. Herz, Detroit, Mich., assignor to
 Borg-Warner Corporation, Chicago, Ill., a corporation of Illinois

Application April 27, 1938, Serial No. 204,665

3 Claims. (Cl. 257—9)

The invention relates to heat exchange units such as used in various arts for the transfer of heat from one fluid to another. As usually constructed, such units are designed for exchange of 5 heat between only two fluids, such for instance as the heating of air by steam or hot water radiators, or the cooling of air by a refrigerant. Also, in some instances, the exchange is between two 10 liquids instead of between a liquid and a gas. Units which are designed for use in heating systems are not usually adapted for use with cooling 15 systems and where, as in some instances, it is desirable to alternatively heat or cool, distinct units are employed for the respective purposes.

It is the object of my invention to obtain a single unit adapted for alternative use in either heating or cooling a fluid medium passed therethrough, as for instance for either heating or 20 cooling air, or for other analogous uses. To this end the invention consists in the construction as hereinafter set forth.

In the drawings:

Figure 1 is a side elevation, partly in section, 25 of one form of my improved multiple heat exchange unit;

Figure 2 is a plan view thereof with parts broken away;

Figure 3 is a side elevation with parts broken away.

As illustrated in Figures 1 to 3, A and B are spaced headers which are connected with each other by a plurality of rows of tubes C, C', etc., arranged in parallel relation. Intermediate these rows are additional rows of tubes D, D', etc., extending between the headers, but these tubes instead of communicating with the interior of the header pass completely through the same and are connected to each other by return-bend conduits E. The tubes C, C' and D, D' in adjacent rows are staggered, the arrangement being such as to form a series connection between the alternate tubes in successive rows D, D', etc., while at opposite ends of the series said tubes are connected to cross headers F and G arranged respectively adjacent to the headers A and B. The headers A and B are respectively connected with conduits H and I for the inlet and outlet of the fluid medium and the headers F and G are similarly connected to inlet and outlet conduits J and K. Extending transversely across all of the rows of tubes and in thermal conductive relation thereto are fins L which divide the space into comparatively small transversely extending channels. Side plates M connecting the headers A and B serve to hold the same in rigid relation and to also enclose the space traversed by the tubes and fins.

The construction as just described is adapted 60 for use in alternatively heating or cooling air.

The heating fluid such as hot water or steam enters the header A through the conduit H and after passing through the rows of tubes C, C', etc., into the header B leaves through the conduit I. The air is forced by any suitable propelling 5 means through the transversely extending channels between the fins and tubes and as the fins form conductive means between the tubes C, C', etc., and the tubes D, D', etc., the latter will also constitute a part of the heating surface for 10 transferring heat to the passing air. When it is desired to cool the air the heating fluid is drained from the headers and tubes and any one of the well known refrigerating agents is passed through the tubes D, D', etc., and the connecting return-bend conduits E. Here again the fins L will 15 conduct the heat from the tubes C, C', etc., into the tubes D, D', etc., so that the former also act as a part of the cooling surface.

What I claim as my invention is:

1. A heat exchange unit comprising spaced 20 headers, a plurality of parallelly arranged conduits extending between said headers and in communication therewith for the passage of fluid therethrough, a plurality of additional conduits interspersed with said first mentioned conduits and extending completely through said headers, return-bend connections between said additional conduits for passing a distinct fluid in series 25 therethrough, and means for directing a third fluid transversely between and in contact with 30 all of said conduits.

2. A heat exchange unit comprising spaced 35 headers, a plurality of parallelly arranged conduits extending between and communicating with said headers for the passage of fluid therethrough, additional conduits interspersed with said first mentioned conduits extending completely through said headers, return-bend connections connecting said additional conduits for the passage of 40 a different fluid in series therethrough, and fins extending between and in contact with all of said conduits forming transversely extending channels for the passage of a third fluid.

3. A heat exchange unit comprising spaced 45 headers, a plurality of rows of parallelly arranged conduits extending between said headers and communicating therewith for the passage of fluid therethrough, additional conduits interspersed between the first mentioned conduits in each row 50 and in staggered relation in successive rows, obliquely arranged return-bend conduits connecting in series said additional conduits in successive rows for the passage of a different fluid therethrough, and fins extending transversely between all of said conduits forming channels for 55 the passage of a third fluid therethrough.
